UNITED STATES PATENT OFFICE.

PERRY S. BAUER, OF CHICAGO, ILLINOIS, ASSIGNOR TO BAUER & BLACK, OF CHICAGO, ILLINOIS, A CORPORATION OF ILLINOIS.

SURGICAL-BANDAGE PACKAGE.

1,087,916.

Specification of Letters Patent. Patented Feb. 24, 1914.

Application filed February 5, 1910. Serial No. 542,294.

To all whom it may concern:

Be it known that I, PERRY S. BAUER, a citizen of the United States, residing at Chicago, county of Cook, and State of Illinois, have invented certain new and useful Improvements in Surgical-Bandage Packages, of which the following is a specification.

My invention relates to surgical bandage packages of the type which are usually sold to the trade by the pound, and to the method of putting up the packages ready for sale and use.

It is an object of my invention to provide a package of this character which shall maintain the bandage in a thoroughly antiseptic condition, which will adequately protect the bandages, and which can be easily and readily opened when the contents are needed.

As is well known, bandages of this character are now generally sold by the manufacturer by the pound, and it is very desirable that the package in which the bandages are wrapped shall be as light as possible, and still afford ample protection to the contents.

It is an aim of my invention to provide a package which shall be light, strong, and durable, and from which the contents may be easily and quickly removed without tearing the wrapping.

In the accompanying drawings illustrating a preferred embodiment of my invention, Figure 1 is a plan of a bandage roll. Fig. 2 shows the roll as partially wrapped in the primary or first covering. Fig. 3 is an end elevation of Fig. 1. Fig. 4 is an end elevation of Fig. 2. Fig. 5 is a perspective of the roll with the primary wrapping and one cap in position, and the other cap about to be applied thereto. Fig. 6 is a plan showing the jacket or casing as partially applied to the covered roll, and Fig. 7 is an elevation of the completed package.

Referring to the drawings, 8 designates the bandage material wrapped up tightly in a long roll. A strip of impervious material 9, preferably paraffin paper, sufficiently flexible, slightly longer than the circumference of the bandage roll and of a width substantially equal to the length of the roll, is wrapped tightly around the roll completely covering and inclosing the longitudinal sides thereof. This strip of impervious material is not sealed or fastened

on the roll by wax, mucilage, or any other adhesive, but is mechanically held in place in any suitable manner until the application of the caps 10 prevent it from unrolling. Each cap 10 is formed from a circular disk 60 11 (Fig. 5) of impervious material, preferably paraffin paper like the primary covering 9. One of these disks is placed over each end of the roll and the outer edges thereof are crushed or folded down longitudinally of the roll so that the edges overlap the primary covering 9 and retain it in position. It will be apparent that the bandage roll proper is now completely inclosed by a wrapping of paraffin paper or any suitable impervious material, the longitudinal sides being protected by the primary wrapping 9, and the ends completely inclosed and protected by the caps 10 formed from the disks 11. 75

In order to retain the protective covering of impervious material in position on the roll, I wrap the covered roll in a jacket or casing 12, which comprises merely a strip of relatively inflexible material preferably 80 heavier than the primary covering 9 such as card board or very stiff paper of a width substantially equal to the length of a roll. One edge of the strip is preferably supplied, as at 13, with mucilage. This strip 12 is 85 wrapped tightly around the covered bandage roll and, as shown in Fig. 6, it embraces the depending portions of the caps 10 and securely maintains the protective covering in position. When the outer casing or jacket 90 has been applied and sealed, a completed package, as shown in Fig. 7, of neat appearance and with no projecting edges or flanges, results.

In the package as completed, the bandage 95 roll is maintained in antiseptic condition by the impervious wrapping with which it is entirely inclosed both on its sides and ends and is adequately protected against rough usage in handling by the outer casing or 100 jacket of relatively stiff material; and furthermore, it affords no projecting edges which could be accidentally torn or broken away, thereby admitting air and dirt to the interior of the package. 105

When it is desired to open a package, the bandage roll with its protective covering, is simply pushed out through one end of the outer casing or jacket, whereupon the end caps may be readily removed as they 110

are not secured by any adhesive, and the primary wrapping can be removed without trouble.

The package is simple in construction, 5 easy to make, is strong and durable, and it does not materially add to the weight of the bandage roll, which is a very desirable feature as has been previously explained, where the bandage packages are sold by the pound.

10 While I have shown and described a preferred embodiment of my invention and the preferred method of making the same, it will be understood that various changes in minor mechanical details of structure and 15 of procedure in the manufacturing as well as in the nature and weight of material forming the various coverings, may be resorted to without departing from the spirit of the invention or the sacrificing of any 20 of the material advantages thereof.

What I claim is:

A bandage package comprising a bandage roll, a sheet of light impervious material of width substantially equal to that forming the roll wrapped about the roll, a sheet of 25 light impervious material of superficial area materially greater than the end of said roll disposed across each end and folded down around the roll to inclose the ends of the roll, and a single sheet of relatively heavy 30 material of width equal substantially to the length of the roll wrapped about the roll and about the folded portions of the sheets embracing the ends of the roll and having its ends overlapped and secured together. 35

PERRY S. BAUER.
